6 Claims. (Cl. 249-2)

ABSTRACT OF THE DISCLOSURE

This invention relates to a type of lamp intended particularly for use with television sets. The lamp comprises appropriately wired and longitudinally movable telescopic tubular elements and a switch for operating bulbs positioned in opposite ends of the tubular elements. The tubular elements are associated through a spring element, the tension of which may be overcome to allow securing the lamp to the back of a television set by spaced hook elements.

This invention relates to improvements in television lamps and, more particularly, to a type of lamp which on being attached to the rear wall of a television set and lighted will brighten up the surroundings therebehind.

The principal object of the present invention is to provide an extensible lamp for attachment to the perforated rear ventilation wall usually found on a television set, including a plurality of spring-urged telescopic tubular elements provided at their offstanding end portions with receptacles which are adapted to contain illuminable lamps as well as reflector means which are positioned adjacent thereto, thereby furnishing an increased amount of illumination.

Another object of the invention is to provide longitudinally aligned hook means on each of the telescopic elements which facilitate assembly of the television lamps with the perforations in the rear wall of the television set.

Still another object of the invention includes means for holding the telescopic elements in substantially abutted relation thereby reducing the length of the lamp for shipment or storage.

A further object of the invention is to provide in adjustable reflecting means which includes guide or stop means adapted to cooperate with the contour of the bulb and to prevent complete withdrawal thereof when a bulb is positioned in the sockets of the receptacle.

A still further object of the invention is to provide multiple switch control means for manual actuation of the television lamp as well as automatic switch means therefor which are under the control of the television set.

Other objects and advantages of the invention will be hereinafter described or will become apparent to those skilled in the art and the novel features of the invention will be defined in the appended claims.

In the accompanying drawings:

FIG. 1 is a side elevational view of the improved television lamp in its shortened form for storage or shipment;

FIG. 2 is also a side elevational view of the television lamp shown in FIG. 1 and in which the telescopic elements have been elongated preparatory to attachment thereof to a television set;

FIG. 3 is a cross-sectional view on line 3-3 of FIG. 2;

FIG. 4 is a cross-sectional view on line 4-4 of FIG. 2;

FIG. 5 is a side elevational view generally similar to the device shown in FIG. 1 and in which a different type of spring is used;

FIG. 6 is also a side elevational view of the device shown in FIG. 5 and in which the spring is of the type

2

which elongates the telescopic elements preparatory for attachment to a television set;

FIG. 7 is a fragmentary perspective view of one telescopic element showing the removable reflector means;

5 FIG. 8 is a front elevational view showing a modified form of the television lamp adapted for attachment to the television set;

FIG. 9 shows one circuit layout for automatically illuminating the television lamp when the television set is turned on; and

10 FIG. 10 is another circuit layout including a thermorelay which prevents the television lamp from being illuminated until the television set becomes warm.

Turning now to the drawings there is shown in FIG. 1 a side elevational view of the new television lamp denoted generally at 10 which includes a pair of slidably arranged telescopic elements 12 and 14 which are retained in abutted shortened relation for shipping or storage by means of the tension spring 16, the free ends of each of 20 which are fastened to pins 18 and 20 carried by each of the telescopic elements. The entire device is electrically wired and ready for use and included at the diametrically opposed end of the television lamp element are lamp receptacles 22 and 24 which are equipped with bulbs 26 and 28 and suitable reflective means 30 and 32 which are shown as elongated portions that extend beyond the back wall of the television lamp 10. These reflector means may be integrally formed as a part of the television lamp or 25 slidably mounted in guide means as will be described hereinafter in greater detail.

It is to be understood that although as shown in the figures in the drawings and best shown in FIG. 3, the cross-sectional area of these telescopic elements is substantially square, they may assume any other suitable substantially tubular configuration.

40 A manually operated switch means 34, which is included for the purpose of illuminating the television lamp when desirable, is provided, although, as will be pointed out later herein, this type of switch is not necessary since the television lamp can be connected into the circuitry of the television set to which it is attached and thus lighted when the set is turned on.

45 The view of the device shown in FIG. 2 differs from that in FIG. 1 only in that the spring 16 is shown extended and with the telescopic elements of the lamp moved longitudinally of each other preparatory to fastening the television lamp to the perforated back panel (not shown) of the television set by means of suitable hooks which may take the form of struck-out tongues 36-36 or any other suitable configuration.

50 In FIG. 3 there is shown a cross-sectional view through the lower telescopic element on line 3-3 of FIG. 2 clearly illustrating the manner of slidably associating the telescopic elements, each of which includes guide means extending longitudinally of their inner rear walls and wherein the telescoping element 12, which encompasses telescopic element 14, includes inturned flange means 38-38 into which longitudinally extending tongues 40-40 extend thereby facilitating guidance of the respective elements as they are moved relative to each other.

55 FIG. 4 is a sectional view on line 4-4 of FIG. 2 showing a stop pin 42 carried by the rear wall of telescopic element 12 which is adapted to cooperate with the elongated slot means 44 provided in the rear wall of telescopic element 14. It is to be noted that the slot 44 terminates above the lower extremity of telescopic element 14, as at S, thereby preventing inadvertent separation of the respective elements when they are pulled apart preparatory to assembly of the device with the television set.

60 70 In a further embodiment of the invention shown in FIG. 5, it will be noted that the overall design and construction

of the television lamp generally approximates that shown in FIG. 1 except that in this instance each of the telescopic elements 12' and 14' are provided with an inwardly projecting ledge 16' and 18' respectively, each of which is adapted to support diametrically opposed sleeve-like members 20' and 22', respectively. The sleeves 20' and 22' confine a compression spring 24' which, when the pin-like means 26' is removed from the aperture provided in telescopic element 14', will cause the inner telescopic element 12' to be extended into a position such as that shown in FIG. 6, at which time the prongs or hook-like means 28'-28' may be inserted into the perforations provided in the rear wall of the television set.

In FIG. 7 there is shown a fragmentary perspective view of still a further modified form of the invention in which the means taught therein are adaptable to either of the forms of the invention described in connection with FIGS. 1-2 and 5-6.

For purposes of a clear understanding of this embodiment of the invention a fragmentary portion of telescopic element 12 is shown. As distinguished from the other embodiments of the invention previously referred to and in lieu of having a fixed or immovable reflective means of the type shown at 30 and 32 in FIG. 1, it is contemplated that there be included herein a rigid longitudinally extending hose or support member 50 formed as a part of the rear wall of the lamp 10 which is provided with diametrically opposed internal flanged portions 52-52 which permit slidable movement therebetween of the reflective element 54.

Offstanding from the inner surface of the reflective medium 54 which may comprise a polished metal plate, is a stop means 55 that is secured to said plate in any suitable manner the right angularly extending wing-like portion of which may be adapted to conform to the exterior configuration either of the socket of the lamp or its glass envelope.

As shown at 56-56 the flanged portions 52-52 are depressed toward the hose member 50 to thus provide a frictional gripping means on the reflector 54 to thereby prevent its being inadvertently detached from its support when e.g. it is shipped without the benefit of a lamp being provided in the socket.

In FIG. 8 there is provided at 60 a connection for the current supply cable 62 for the television lamp and the television set.

As described hereinbefore 34 is the button of the on-switch of the television lamp and at 64 a connection is provided for a plug 66 which is carried by the television set. On the instrument, according to FIGS. 8 and 9, the plug 64 of the television lamp is fixed into the socket of the set. The television set is then operated by push button 34 by virtue of the leads 68 connecting the supply circuit 62 for the lamp to the power circuit of the television set.

In FIG. 10 there is shown a thermo-relay 70 connected in one of the leads 68. With this arrangement synchronous on and off switching is effected for both the lamp and the television set. Thus, when the television set is turned on in the conventional manner, a slight voltage drop occurs across the thermo-relay which passes the required amount of current to operate switch 72 only after a preselected period of time corresponding to the warm-up time of the television set. Accordingly with such a circuit arrangement a satisfactory operation of the television set is effected wherein on and off switching of the lamp is synchronous with the on and off switching of the television set.

Although several embodiments of the invention have been depicted and described, it will be apparent that these embodiments are illustrative in nature and that a number of modifications in the apparatus and variations in its end use may be effected without departing from the spirit or scope of the invention as defined in the appended claims.

That which is claimed is:

1. An article of manufacture comprising at least two telescopic tubular elements provided at their diametrically opposed end portions with electrically wired socketed cap means adapted to receive lamps therein, spring means associated with each of said telescopic tubular elements and adapted to increase the longitudinal extent thereof, offstanding longitudinally aligned hook means carried by each of the telescopic tubular elements adapting the device for assembly to a perforated surface, and switch means carried by one of said elements for controlling current supplied to said socketed cap means, whereby the lamps positioned therein may be illuminated.
2. A device of the type described in claim 1, wherein each of said telescopic tubular elements are provided at their longitudinal extremities adjacent to said socketed cap means with offstanding reflecting means.
3. A device of the type described in claim 1, wherein means are provided for overcoming the force of said spring means thereby reducing the longitudinal extent of said telescopic tubular elements and facilitating storage of said device.
4. In an extensible television lamp for attachment to the rear wall of a television set, the combination comprising a plurality of telescopic tubular elements provided at their offstanding end portions with electrically wired socketed cap means adapted to receive illuminable lamps, longitudinally aligned reflecting means associated with the offstanding end portions, aligned fastening means carried by said telescopic tubular elements adapted to mount said television lamp on the rear wall of a television set, spring means interposed between said telescopic tubular elements for elongating said elements, switch means for controlling current supplied to said illuminable lamp and locking means for restricting movement of said telescopic tubular elements to an inoperative position to facilitate storage.
5. A device of the type described in claim 4, wherein the diametrically opposed end portions of said telescopic tubular elements are provided with longitudinally aligned support means including said reflective means.
6. A device of the type described in claim 5, wherein said longitudinally aligned reflective means are adjustably mounted relative to their support means.
